UNITED STATES PATENT OFFICE.

DANIEL ADAMS, OF NEWTON, MASSACHUSETTS.

COMBUSTION-CONTROLLING SYSTEM.

Application filed August 14, 1919. Serial No. 317,453.

To all whom it may concern:

Be it known that I, DANIEL ADAMS, a citizen of the United States, and resident of Newton, county of Middlesex, State of Massachusetts, and whose post-office address is 91 Allerton Road, Newton Highlands, Massachusetts, have invented an Improvement in Combustion-Controlling Systems, of which the following description, in connection with 10 the accompanying drawing, is a specification, like characters on the drawing representing like parts.

This invention relates to a system or apparatus for automatically controlling combustion so as to secure under various and varying conditions a predetermined relation between the amount of fuel fed to the combustion chamber and the amount of air supplied.

20 The invention is susceptible of a wide range of application but is of particular value in such cases as furnaces to which the coal is fed by automatic stokers or oil burning furnaces wherein the rate at which the fuel is fed is under control.

The object of the invention is to secure accurate control of the flow of air through the furnace or combustion chamber by either eliminating or controlling all the variables 30 which affect the flow.

It is usual to regulate the supply of air to the combustion chamber by constricting, as with a damper, at some point the passageway through the furnace for the air and 35 gases and to vary the area of constriction as by setting the damper at a predetermined position for each load or each rate of flow of the fuel to the combustion chamber. But, such systems fail to take into consideration 40 or to control a number of variable factors which affect the flow of air. The quantity of air which will pass a regulating damper is a function not only of the area of the damper opening, but also of the differential 45 in pressure at that opening. In order therefore to secure accurate control of the quantity of air passing the damper opening, both of these factors must be under control. There are many variable factors affecting the 50 draught or the quantity of air passing through the damper opening among which may be mentioned the weather, the temperature of the exit from the combustion chamber, leakage into the combustion chamber, 55 and when a boiler is being heated such factors as the extent of the collection of soot,

the tightness of the baffles, and the leakage through the boiler setting.

The present invention provides means for automatically correlating the differential in 60 pressure at the damper opening and the area of the damper opening to secure a predetermined relation between the quantity of air flowing past the damper opening and the amount of fuel fed to the combustion chamber. 65

70 Preferably the object of the invention is secured by means for maintaining a substantially constant differential in pressure at the damper opening whereby the quantity of air passing the damper opening is a function of or proportional to the area of the damper opening alone, and in providing means for varying the position of the damper or the area of the damper opening in predetermined relation to the amount of fuel fed 75 which consequently results in the amount of air passing the damper opening having a fixed or predetermined relation to the amount of fuel fed. 80

85 More specifically the invention includes means such as a load regulator which acts to set a regulating damper in the passageway for the air and gases through the combustion chamber at a predetermined position for each load together with a draught regulator which acts to control a second damper in the said passageway to maintain a constant differential in pressure at the regulating damper. 90

95 The nature and object of the invention will appear more fully from the accompanying description and drawings and will be particularly defined in the claims.

As specific and illustrative embodiments of the invention the drawings show boiler heating furnaces in which the fuel is either coal fed by an automatic stoker or oil fed through a burner all of a familiar type. 100

In the drawings Fig. 1 is a side elevation largely diagrammatic of a boiler, subjacent furnace or combustion chamber, automatic coal stoker, and an apparatus in connection therewith for carrying out one form of the invention. 105

Fig. 2 is a detail partially in vertical cross section of a draught regulator shown in Fig. 1.

Fig. 3 is a detail partially in vertical cross section of the device through which the draught regulator shown in Fig. 2 acts to position the second damper. 110

Fig. 4 is a detail partially in vertical cross section of a cylinder and plunger shown in Fig. 2 and connected with the blade of the draught regulator.

5 Fig. 5 is a view in side elevation partially in vertical cross section of the load regulator shown in Fig. 1.

10 Fig. 6 is a view in side elevation of the device through which the governor shown in Fig. 1 acts to position the regulating damper.

15 Fig. 7 is a view in front elevation of a pair of boilers provided with subjacent oil heating furnaces, the one at the left hand

20 being illustrated as provided with an apparatus embodying the invention designed to maintain a substantially constant differential in pressure at the ash pit door by maintaining the pressure in the ash pit substantially constant, and less than that of the atmosphere, while the one at the right hand is illustrated as provided with an apparatus embodying the invention in which the differential in pressure at the ash pit door 25 is varied to a predetermined amount for each variation in the load.

20 Fig. 8 is a view in side elevation of the construction shown at the left hand side of Fig. 7.

30 Fig. 9 is a detail in side elevation and partially in vertical cross section of the draught regulator and connections for the boiler at the right hand side of Fig. 1.

35 Fig. 10 is a view chiefly in vertical cross section of the valve for controlling the oil supply in Fig. 7.

40 Fig. 11 is a view chiefly in vertical cross section of the valve for controlling the steam supply in Fig. 7.

45 Fig. 12 is a view similar to the lower portion of Fig. 1 showing the mechanism on a larger scale.

With the present invention embodied in a furnace provided with an automatic stoker 45 where the rate of feeding of the coal is under control, the quantity of air may be correctly proportioned to the amount of coal fed and consequently a high efficiency of combustion secured.

50 As the invention is not concerned with the details of construction of the combustion chamber, furnace, boiler, or other devices, and the stoker, these elements have been illustrated chiefly diagrammatically.

55 In the construction shown in Fig. 1 the combustion chamber 1 is located beneath a steam boiler 2; air is supplied beneath the fuel bed 3 from a conduit 4 under a pressure greater than atmospheric. Coal is fed to the 60 fuel bed 3 by a suitable automatic stoker. The coal being supplied to the hopper 4 and pushed therefrom by a piston or plunger 5 operating therebeneath and driven by a connecting rod 6 connected to a crank 65 7 on a shaft 8 geared to a shaft 9 driven in

turn by a belt 10 from a pulley 11 rotated by a steam engine 12.

A device such as a suitable fly ball governor 13 is geared to some element such as a shaft 9 having a movement directly proportional to the amount of fuel fed and this governor is connected to a regulating damper such as the vertically sliding plate 14 placed in the air conduit 4 in such a manner that the regulating damper is thereby moved to vary the opening of the conduit at the damper in direct proportion to the amount of fuel fed to the combustion chamber.

Suitable means are provided for varying the amount of fuel fed to correspond with the requirements such as the load upon the boiler. For this purpose there may be employed and there is herein illustrated a load regulator of the type shown in the patent 85 to Atchison et al. reissue No. 13,337 granted December 12, 1911. This load regulator is connected by a pipe 15 to the steam space of the boiler 2 and acts to control the valve 16 in the steam admission pipe 17 running to the engine 12. As the load on the boiler rises and falls, the amount of steam fed to the engine is by the load regulator correspondingly increased or diminished and thus the amount of fuel fed to the combustion chamber is similarly increased or diminished.

The load regulator is shown in detail in Fig. 5 and needs no detailed description in view of its disclosure in the aforesaid patent. The steam from the boiler passing through the pipe 15 acts against a diaphragm in the chamber 18 moving the rod 19 in opposition to a system of weighted levers. The force of the steam is thus opposed by the weights 20 and 21. In addition to the provision for varying the amounts of the weights 20 and 21, a spring 22 is provided which acts to steady the movement of the parts. When the steam pressure in the boiler rises or falls the rod 19 is moved to rock the lever 23 and through it the auxiliary lever 24 thus raising or lowering the connecting rod 25 extending to the water valve 26 in the piston 27, in turn causing the water propelled piston 27 to move in the same direction and through its connection with the lever 28 effect through the flexible connector 29 the operation of the valve 16 to decrease or increase the supply of steam to the engine which operates the stoker.

As a convenient means for securing the operation of the regulating damper 14 from the governor 13 already described, a water controlled piston such as shown in cross section in Fig. 5 may be employed. Such a device is illustrated in side elevation in Fig. 6. The connecting rod 30 of this device which corresponds to the connecting rod 25

is connected by an L-shaped rod 31 to the vertical sliding collar 32 of the governor 13 while the piston rod 33 extending downward from the water piston is connected by a flexible connector 34 to the regulating damper. Thus, as the balls of the governor 13 move out and in with the increase or decrease in the amount of coal fed by the stoker, the connecting rod 30 rises and falls and the 10 water piston falls and rises to effect the opening and closing movement of the regulating damper 14.

Such a mechanism as thus far described thus acts to vary the area of opening at the 15 regulating damper 14 proportional to or in a predetermined ratio with respect to the amount of coal fed to the combustion chamber by the stoker.

As a simple and preferred means of controlling the differential in pressure at the regulating damper opening a second damper 20 35 is placed in the passageway for the air and gases through the combustion chamber and is shown as being placed in the air conduit 4 intermediate of the regulating damper and the stoker.

The second damper 35 is controlled by a pressure regulator designed to respond to very small differences in pressures. In itself 25 it is a familiar device and operates on a similar principle to that of the load regulator already described. In the form herein used, and shown in detail in Figs. 2, 3, and 4, a closed box or casing 36 is connected at 30 opposite sides to the passageway 4 at opposite sides of the regulating damper 14 so that the pressures at opposite sides of this regulator are conveyed into the opposite sides of the box 36. Within the box 36 and 35 closely fitting the walls is a vertical blade 37 nicely balanced and pivoted with an anti-friction pivot at 38. The balancing weight 39 is so formed or adjusted that when the predetermined differential in pressure exists 40 the blade 37 will stand in its central or vertical position. Any slight change in the differential in pressure will therefore cause the blade 37 to swing in one direction or the other. When it thus swings it acts through 45 the arm 40 to raise the rod 41 and with it the valve 42 admitting water from the water pressure system to one or the other of the pipes 43 and 44 connecting above and below the piston 45 in the cylinder 46, and thus 50 effecting the movement of that piston and through the rod 47 extending therefrom the movement of the damper 35.

Thus, it will be seen that this mechanism acts automatically to maintain a given constant differential in pressure at the opening 55 of the regulating damper 14 at all times and under all conditions, assuming only that the draught out from the combustion chamber is adequate. The quantity of air passing the 60 regulating damper 14 becomes therefore a

function solely of the area of the damper opening. Consequently the quantity of air is readily proportioned in any required or predetermined ratio to the amount of fuel fed to the combustion chamber. 70

The principles of the invention are further illustrated by the application thereof to an oil burning furnace. One form of such a furnace is shown in front elevation at the left hand side of Fig. 7 and in side 75 elevation in Fig. 8, but no attempt has been made to illustrate details of the construction.

A steam boiler 48 is here shown mounted above a combustion chamber therebeneath closed exteriorly by the doors 49. Beneath the combustion chamber is the usual ash pit chamber provided with openings at the front controlled by doors or dampers 50. The smoke box on the boiler 40 is connected by a flue 51 with a transverse header flue 52. 80 85

The oil may be fed to the fire box by any suitable and well known method. As herein shown the oil is fed in and mixes with steam under pressure. The oil pipe 53 leads from a suitable source of oil supply through a 90 controlling valve 54 to the burner 55 projecting into the combustion chamber. The steam pipe 56 leads from a suitable source of steam supply such as the boiler itself through a controlling valve 57 to the burner 95 55 and acts to inject the oil into the combustion chamber in a well known manner.

The oil controlling valve 54 is shown somewhat in detail in Fig. 10 and the steam controlling valve 57 in Fig. 11. These valves 100 may be operated in any suitable manner to secure the required ratio between the amount of oil and steam mixing in the burner 55. For this purpose a shaft 58 is shown extending at the front of the boiler and mounted in 105 suitable bearings 59. This shaft carries pulleys or cams 60 and 61 above the oil and steam controlling valves respectively. The connections to these valves are similar. A lever 62 is fulcrumed at 63 on a bracket 64 110 projecting upwardly from the oil valve. This lever is pivotally connected at 65 to the valve plunger 66 and at its opposite end 67 is connected to a flexible connector 68 extending up over and secured to the pulley 115 or cam 60. A counter weight 69 is hung from the point 67 of the lever. Thus, as the shaft 58 is turned the oil controlling valve is opened and closed at a rate and to an extent depending upon the proportions of the 120 lever 62 and the size of configuration of the pulley or cam 60. In a similar manner the lever 70 of the steam controlling valve 57 operates the plunger 71 by the flexible connector 72 extending over the cam or pulley 125 61. Any required ratio between the amount of the openings of the oil and steam valves to affect the required ratio between the oil and steam mixing in the burner may be obtained by varying the proportion, size, and 130

shape of the various connections. One simple means is afforded by varying the point at which the flexible connector is connected to the lever operating the valve as shown in the case of the steam controlling valve where the connector 72 may be connected to any one of the holes 73 in the lever 70.

Similar means to those already described are illustrated for effecting the control of the quantity of air supplied to the combustion chamber and the amount of the fuel fed thereto. Two dampers are provided as heretofore, one a regulating damper and the other a damper for maintaining the constant differential in pressure at the opening of the regulating damper. As has already been pointed out, these two dampers may be placed anywhere in the passageway for the air and gases through the combustion chamber. As herein shown one damper is placed at the ash pit door or at the point where the air is admitted from the atmosphere and the other is shown as placed in the flue or stack leading out from the combustion chamber.

In this case the doors 50 of the ash pit constitute the regulating damper and operate together. They are operated by flexible connectors 74 extending to levers 75 on the shaft 58. Consequently any required or predetermined ratio between the area of the opening at these dampers and the amount of fuel fed to the burner is readily and easily obtained.

In order to maintain the substantially constant differential in pressure the ash pit behind the doors or regulating damper 50 is connected by a conduit 76 with a draught regulator 77 of the type already described. As in this case the pressure at the outside is atmospheric, the casing of the draught regulator at one side of the blade is open to the atmosphere and at the other side is closed to form a chamber into which a conduit 76 from the ash pit extends.

This draught regulator 77 acting through a device 78 similar to that shown in Fig. 4 and a device 79 similar to that shown in Fig. 3 operates the damper 80 in the flue to maintain the substantially constant differential in pressure at the regulating dampers with the pressure in the ash pit below atmospheric.

The amount of fuel fed to the combustion chamber is shown as regulated to correspond with the load on the boiler by a load regulator 81 mounted at the side of the boiler and of the type already described and shown in Fig. 5. The connector 82 actuated by the load regulator is shown as extending to and connected to a pulley 83 on the shaft 58.

Thus, as the load on the boiler rises and falls the shaft 58 is rotated in one direction or the other by the load regulator.

Thus far the principles of the invention

have been illustrated in connection with applications wherein substantial constant differential in pressure was designed to be maintained at the opening of the regulating damper, but the relation between the quantity of air supplied and the amount of fuel fed may also be controlled by varying the differential in pressure at the regulating damper with the load. In this case the differential in pressure at the regulating damper will still be a predetermined amount for each load, but it will not be the same amount for all loads.

As an illustration of this application of the principles of the invention, a construction such as shown at the right hand side in Fig. 7 and in Fig. 9 may be employed. The construction illustrated for this purpose is that of an oil burning furnace similar in substantially all respects to that already described excepting the control of the draught regulator. In order that the differential in pressure at the regulating damper may vary with the load means must be provided to affect the blade 84 of the draught regulator shown in Fig. 9 in accordance with the variation in the load. This may be accomplished in a simple manner by providing a cup 85 secured to the blade 84 and by providing a chain 86 secured to and extending from a cam or pulley 87 on the shaft 88 controlled by the load regulator. These parts are so proportioned that for each change in the load as a result of which the load regulator turns the shaft 88 in one direction or the other, an amount of chain is dropped into or lifted out of the cup 85 sufficient so to effect the balance of the blade 84 as to vary the differential in pressure maintaining the blade in its central position and thus to affect the control of the flue damper 89 accordingly. The basic principles underlying the main feature of the invention involving the adjustable regulating damper such as 14 and the automatic differential pressure controlling damper such as 35 for regulating the flow of air or gas under pressure through the passageway or conduit are separately illustrated on a larger scale in Figure 12. The construction here illustrated which, as in the other figures, is more or less diagrammatic in nature, is the same as that illustrated on a small scale in Figure 1. The passageway is formed by the conduit 4 and the flow of air or gas is assumed to be in the direction of the arrow 90. The regulating damper 14 is shown as sliding vertically in the conduit and adjustable by any suitable means to vary the area of the passageway or in other words to provide at this point a variable or adjustable constriction of the passageway. The automatic differential pressure controlling damper 35 is shown in the same conduit 4 and acts on the principles set

forth to control the differential in pressure at the point of constriction or at the damper 14 in the passageway so as to maintain a predetermined or constant differential in pressure at this point, or in other words to control the differential in pressure at this point, that is at the regulating damper. Thus the quantity of air or gas flowing past the area of constriction or past the damper 14 is automatically controlled and in the particular form illustrated automatically maintained at a predetermined constant.

The closed box or casing 36 as already described is connected by the feeler pipes 91 to the passageway 4 at opposite sides of the point of constriction or damper 14. Thus the pressures at the opposite sides of the damper are conveyed into the casing 36 to opposite sides of the vertical blade 37 pivoted at 38 and adjustably balanced by the weight 39. As already pointed out the weight 39 is preferably adjusted so that the blade 37 will stand in a central or vertical position when the predetermined differential in pressure exists. All the parts would be in substantially the position illustrated under these circumstances. In this position it will be noted pressure controlling damper 35 stands midway of its opened and closed positions and the valve 42 stands so as to close the end of pipes 43 and 44. Thus the water or fluid under pressure fed into the valve casing 92 through the pipe 93 is cut off from the pipes 43 and 44. Consequently the piston 45 is held against vertical movement by the water there beneath in the cylinder 46, consequently the damper 35 is maintained in its midway position.

If now for example the pressure is reduced at the left hand side of the damper 14 the blade 37 will swing to the left depressing the piston 42 until the pocket 94 therein extends over the ends of the pipes 43 and 44 and serves to connect them. This permits the water beneath the piston 45 to escape or be forced out through the waste 95 or into the space above the piston 45 allowing the piston 45 and its connecting rod 47 which, if not sufficiently heavy, may be weighted to sink swinging the damper 35 toward its closing position. This immediately acts to restore the required differential in pressure.

If the differential in pressure at the damper 14 is disturbed so as to swing the plate 37 to the right, then the piston 42 is raised until it closes the end of the pipe 43 and uncovers the end of the pipe 44 allowing the water or fluid under pressure to pass into the pipe 44 and thence beneath the piston 45 forcing the piston up and opening the damper 35. Any water above the piston 45 in the cylinder 46 may waste out through the vent 95.

The by-pass 96 shown connecting the pipes

43 and 44 is provided with a hand operated valve 97 normally closed. This valve when open, therefore, connects the two pipes relieving the pressure beneath the piston 45 or balancing the pressure in the two pipes, and allowing the piston 45 and the connected parts to sink closing the damper 35. This by-pass and valve are useful, as for example when the device is applied to a furnace and the furnace is banked whereupon the damper 35 should be closed.

The foregoing constructions are presented for the purpose of illustrating the broad principles of this invention and it will be understood that the invention is not to be restricted by reasons of the specific applications disclosed nor otherwise than as by the claims.

Having thus described my invention what I claim as new and desire to secure by Letters Patent is—

1. A combustion controlling system comprising a combustion chamber, a passageway for the air and gases through and including said chamber, a damper in said passageway regulating the flow of air to the combustion chamber, and means for controlling the differential in pressure at the damper whereby the quantity of air flowing past the damper is controlled.

2. A combustion controlling system comprising a combustion chamber, a passageway for the air and gases through and including said chamber, a damper in said passageway regulating the flow of air to the combustion chamber, and means for controlling the relation between the differential in pressure at the damper and the area of the damper opening.

3. A combustion controlling system comprising a combustion chamber, a passageway for the air and gases through and including said chamber, a damper in said passageway regulating the flow of air to the combustion chamber, and means for automatically correlating the differential in pressure at the damper and the area of the damper opening to secure a predetermined relation between the quantity of air flowing past the damper and the amount of fuel fed.

4. A combustion controlling system comprising a combustion chamber, a passageway for the air and gases through and including said chamber, and means for automatically correlating the differential in pressure at a given point in the said passageway with the area of the said passageway at a said given point to secure a predetermined relation between the quantity of air flowing past that point and the amount of fuel fed to the combustion chamber.

5. A combustion controlling system comprising a combustion chamber, a passageway for the air and gases through and including said chamber, a damper in said passage-

way regulating the flow of air to the combustion chamber, and means for maintaining a substantially constant differential in pressure at the damper whereby the quantity of air flowing past the damper is in direct proportion to the damper opening alone.

6. A combustion controlling system comprising a combustion chamber, a passageway for the air and gases through and including 10 said chamber, means for feeding fuel to the combustion chamber, a damper in said passageway, means for varying the position of the damper in accordance with the amount of fuel fed, and means for maintaining a 15 substantially constant differential in pressure at the damper opening whereby the quantity of flow through the damper opening is in direct proportion to the damper opening alone and is consequently proportional to the amount of fuel fed.

7. A combustion controlling system comprising a combustion chamber, a passageway for the air and gases through and including 20 said chamber, means for feeding fuel to the combustion chamber, a damper in said passageway, means for varying the position of the damper, and means for controlling the differential in pressure at the damper opening whereby the quantity of flow through 25 the damper opening may be regulated to correspond with the amount of fuel fed.

8. A combustion controlling system comprising a combustion chamber, a passageway for the air and gases through and including 30 said chamber, means for feeding fuel to the combustion chamber, a pair of dampers located at different points in said passageway means for varying the position of one of 35 said dampers to cause the damper opening 40 to vary in accordance with the amount of fuel fed, and means, controlled by the differential in pressure effecting the flow through said damper opening, acting to vary the position of the other damper to 45 maintain constant the said differential in pressure.

9. The method of regulating furnaces which consists in controlling a constriction 50 in the passageway for the air and gases through the furnace and in controlling the differential in pressure at the point of constriction.

10. The method of regulating furnaces which consists in controlling a constriction 55 in the passageway for the air and gases through the furnace and in maintaining a substantially constant differential in pressure at the point of constriction.

11. The method of regulating furnaces 60 which consists in regulating the flow of air to the furnace by varying a constriction in the passageway for the air and gases through the furnace and in maintaining a substantially constant differential in pressure at the point of constriction.

12. The method of regulating furnaces which consists in regulating the flow of air to the furnace by varying a constriction in the passageway for the air and gases through the furnace and in controlling the differential 70 in pressure at the point of constriction.

13. The method of regulating furnaces which consists in feeding fuel to the furnace, in supplying air to the furnace, in controlling the feeding of the fuel in accordance with 75 the work performed, in regulating the supply of air to the furnace by varying in accordance with the amount of fuel fed a constriction in the passageway for the air and gases through the furnace at a given point, 80 and in maintaining a substantially constant differential in pressure at that point.

14. The method of regulating furnaces which consists in feeding fuel to the furnace, in supplying air to the furnace, in controlling the feeding of the fuel in accordance with the work performed, in regulating the supply of air to the furnace by varying a constriction in the passageway for the air and gases through the furnace at a given 90 point, and in controlling the differential pressure at the point of constriction.

15. The method of regulating furnaces which consists in feeding fuel to the furnace, in supplying air to the furnace, in controlling the feeding of the fuel in accordance with the work performed, in varying in accordance with the amount of fuel fed a constriction in the passageway for the air and gases through the furnace at a given point, 100 and in maintaining a substantially constant differential in pressure at the point of constriction.

16. The method of regulating furnaces which consists in feeding fuel to the furnace, in supplying air to the furnace, in controlling the feeding of the fuel, in varying in accordance with the amount of fuel fed a constriction in the passageway for the air and gases through the furnace at a given 105 point, and in controlling the differential in pressure at the point of constriction.

17. The method of regulating furnaces which consists in controlling a constriction in the passageway for the air and gases through the furnace in accordance with the work performed and in maintaining a substantially constant sub-atmospheric pressure 115 in the ash pit of the furnace.

18. The method of regulating furnaces which consists in regulating the amount of fuel fed to the furnace in accordance with the amount of work performed, in supplying air to the ash pit of the furnace through an orifice varying in accordance with the amount of fuel fed, and in maintaining a substantially constant differential in pressure at the said orifice.

19. The method of regulating the flow of gas under pressure through a passageway 130

which consists in controlling a constriction in the passageway for the gas and in controlling the differential in pressure at the point of constriction.

5 20. The method of regulating the flow of gas under pressure through a passageway which consists in controlling a constriction in the passageway for the gas and in maintaining a substantially constant differential 10 in pressure at the point of constriction.

21. The method of regulating the flow of gas under pressure through a passageway which consists in regulating the flow of gas by varying a constriction in the passageway 15 and in maintaining a substantially constant differential in pressure at the point of constriction.

22. The method of regulating the flow of gas under pressure through a passageway 20 which consists in regulating the flow of gas by varying a constriction in the passageway and in controlling the differential in pressure at the point of constriction.

23. An apparatus of the class described 25 comprising a conduit, a damper in the conduit, means to adjust the position of the damper to vary the area of the conduit at the damper, and means for controlling the differential in pressure at the damper whereby

the quantity of gas flowing past the damper 30 is controlled.

24. An apparatus of the class described comprising a conduit, a damper in said conduit regulating the flow of gas therethrough, and means for controlling the relation be- 35 between the differential in pressure at the damper and the area of the damper opening.

25. An apparatus of the class described comprising a conduit, a damper in the conduit regulating the flow of gas therethrough, 40 and means for maintaining a substantially constant differential in pressure at the damper whereby the quantity of gas flowing past the damper is in direct proportion to the damper opening alone. 45

26. An apparatus of the class described comprising a conduit, a pair of dampers located at different points in the conduit, means for varying the position of one of said dampers to vary the damper opening, 50 and means controlled by the differential in pressure effecting the flow through said damper opening, acting to vary the position of the other damper to maintain constant the said differential in pressure. 55

In testimony whereof, I have signed my name to this specification.

DANIEL ADAMS.
